WINDING MACHINE

Julius Brenzinger, Fairfield, Conn., assignor to
The Max Ams Chemical Engineering Corpora-
tion, Bridgeport, Conn., a corporation of Con-
necticut

Application May 16, 1930. Serial No. 452,890

3 Claims. (Cl. 242—43)

This invention relates generally to winding machines, and especially of the character employed in the winding of rayon.

In the accompanying drawings the invention 5 is disclosed in a concrete and preferred form in which

Fig. 1 is a top plan view of a device embodying the invention;

Fig. 2 is a view of the parts disclosed in Fig. 10 1 shown in end elevation and partly broken away and in section;

Fig. 3 is a view similar to Fig. 2 with the thread 15 guide in the extreme shifted position in one direction and at both ends of the main reciprocating motion; and

Fig. 4 is a view similar to Figs. 2 and 3 but with the thread guide in its other extreme shifted position also at both ends of the main reciprocating motion.

20 1 indicates a rotatable spool associated with which is a thread guide 2. The general operation of machines of this character is that the newly formed thread is led from the setting bath (not shown) through the thread guide to the spool. The thread guide moves back and forth longitudinally over the spool and the latter rotates so as to wind the thread layer upon layer 25 on the spool. For reasons which need not be entered into here, the cylindrical body of thread, 30 3, thus formed should be built up with taper ends 4. Various complicated devices have heretofore been employed to obtain this effect, and the main object and feature of this invention is to simplify the means for accomplishing this purpose.

35 Either or both the spool and the thread guide may be given a main reciprocating motion one with respect to the other. In the present instance, however, there is employed a thread guide carrier 5 which slides in bearings 6, and this carrier is here shown as being provided with a rack 7 engaged by pinion 8, which latter, in turn, is oscillated by another pinion 9 engaged by rack 10 carrying cam rolls 11 actuated by heart-cam 12. It will be understood from this that rotation 40 of cam 12 effects reciprocation of carrier 5, the strokes of said reciprocating movement being of uniform length. Conventional means such as gears 13 and 14 are indicated to rotate the spool, and it will be understood that the gear ratio is 45 such that the spool makes a number of revolutions for each reciprocation of the carrier.

50 Thread guide 2 is mounted on pivot 15 of the carrier, and also mounted on said carrier in bearing 16, and reciprocating therewith, is a rotatable ratchet 17. 18 indicates a stationary

pawl mounted independently of the carrier. It will be seen that when the carrier comes to the end of its stroke in one direction (Fig. 3) pawl 18 will engage the ratchet and turn it a distance of one tooth. 19 is a stop pawl to retain the 50 ratchet in the position to which it has been moved. Ratchet 17 carries a crank 20 and from this crank extends a connection 21 that reaches to arm 22 of the thread guide and with which arm said connection has an adjustable and piv- 55 otal joint 23. It will now be understood that, as carrier 5 is reciprocated, ratchet 17 is turned one tooth to each complete stroke thereby shifting the crank. The movement of the crank is transmitted to the thread guide, through the connections described, and its position is shifted 60 slightly in one direction. This continues during a plurality of reciprocations of the carrier until the effect of the crank is reversed when the thread guide begins to be shifted in the opposite 65 direction and this likewise continues for a plurality of reciprocations of the carrier. In Fig. 3 the thread guide is shown shifted to its extreme position in a right hand direction and is indicated at the end of the stroke of the carrier 70 in both directions. In Fig. 4 the opposite effect is shown.

75 It will now be understood that, although the carrier is given a reciprocating motion having a uniform stroke, yet by shifting the position 80 of the thread guide a variable action is introduced that builds up the cylindrical body with taper ends.

85 It will be obvious that a number of spools and 90 thread guides may be employed and also that the arrangement may be in duplicate as shown.

I claim:

1. The combination of a thread guide and a 95 rotatable spool to receive thread directed by said guide, a thread guide carrier, means to reciprocate the carrier to thereby wind a cylindrical body of thread on the spool, and means to shift the position of said thread guide on said carrier first progressively in one direction during a plurality of the reciprocations and then progressively in the other direction during another plurality of reciprocations to thereby build up, with taper ends, said cylindrical body of thread.

100 2. The combination of a thread guide and a rotatable spool to receive thread directed by said 105 guide, a thread guide carrier, means to reciprocate, with a movement of uniform length of strokes, the carrier to thereby wind a cylindrical body of thread on the spool, and means to shift the position of said thread guide on said carrier 110

first progressively in one direction during a plurality of the strokes and then progressively in the other direction during another plurality of strokes to thereby build up, with taper ends, said 5 cylindrical body of thread.

3. The combination of a reciprocating carrier, a thread guide pivotally mounted thereon, and means to effect by the reciprocation of the car-

rier first a movement of the guide about its pivot in one direction by a plurality of steps during a plurality of reciprocations and then a movement of the guide about its pivot in the other direction by a plurality of steps during 80 another plurality of reciprocations.
